THREE-IN-ONE GARMENT

Anne Nathalie Carlu, New York, N. Y.

Application July 19, 1943, Serial No. 495,325

11 Claims. (Cl. 2—88)

The present invention relates to improvements in garments and has reference more particularly to a lady's convertible outer garment.

This application is a continuation in part of my application Serial Number 469,558, filed December 19, 1942.

One of the important objects of the present invention is to provide a three-in-one garment, namely, a fur coat, a cloth coat and a cape, any one of which can be readily and easily formed from the unitary garment structure.

A further object resides in the provision of a detachable fur sleeve for use when the garment is converted into a fur coat.

Still a further object is to provide a convertible garment that includes a means for closing the shoulder openings and concealing the sleeves of the cloth coat when the garment is to be worn as a cape.

Another important object is to provide a convertible garment of the above mentioned character that will be inexpensive and attractive.

Other objects and advantages will become apparent from the following description when taken in connection with the accompanying drawings.

In the drawings, forming a part of this specification and in which like reference characters designate corresponding parts throughout the several views:

Figure 1 is an elevational view showing the garment being worn as a fur coat.

Figure 2 is an elevational view illustrating the garment when worn as a cloth coat.

Figure 3 is a view showing the garment as being worn when converted into a sleeveless cape.

Figure 4 is a fragmentary enlarged view of the fur coat with the detachable fur sleeve attached.

Figure 5 is a similar view, showing the fur coat with the sleeve of the cloth coat extended and ready to receive the detachable fur sleeve.

Figure 6 is a detail elevation of one of the fur sleeves.

Figure 7 is an enlarged view looking into the shoulder opening, the latter being in its open or unfastened condition and showing the sleeve of the cloth coat disposed within the body of the garment when the latter is to be worn as a cape.

Figure 8 is an enlarged view looking into the upper open end of the detachable fur sleeve showing the "zipper" fastener carried thereby, and

Figure 9 is a vertical sectional view through the garment when worn as a cape, illustrating the manner in which the sleeve of the cloth coat is tucked in or concealed from view.

My three-in-one garment comprises a cloth

coat 10, formed of any suitable fabric material, the same including a body portion 11, sleeves 12 that extend from the shoulder portions 13 and a collar 14.

Also forming a salient part of my improved garment is the fur coat 15, the same comprising a body portion 16, shoulder portions 17 and a collar 18.

The body portion 16 of the fur coat 15 is arranged over the body portion 11 of the cloth coat 10 and is united thereto by any suitable fastening means, including stitching, but preferably a "zipper," buttons, snaps or any other means of detachable engagement that extends along the open front edges of the two coats. Likewise, these two coats are united along the outer edges of the superposed collars to provide a unitary structure.

The shoulder portions 17 of the fur coat are formed with arm openings 19, and as is clearly illustrated in Figure 7, a "zipper" type fastener tape designated generally by the numeral 20 is associated with each shoulder or arm opening 19 and the usual locking slider element 23 is associated with this tape.

Further, forming an important part of the present invention is a pair of detachable fur sleeves 21 one of which is shown in detail in Figures 6 and 8 of the drawings. The upper open end of the fur sleeve 21 also carries a "zipper" type fastener tape denoted by the numeral 22 and its companion locking slider element 24.

Any suitable fur may be employed in forming the fur coat and detachable fur sleeves. It is also to be understood that the sleeves of the cloth coat may be lined in any suitable and well known manner.

While I prefer to employ "zipper" type fasteners, any other type of separable fastener may be equally as well employed, such as buttons and buttonholes, snap fasteners, hooks and eyes and I do not wish to limit myself to any particular type of fastener means.

Likewise, one of the coats may be formed of waterproof material so a raincoat may be provided.

When the garment is to be worn as a cloth coat, the body portion 11, sleeves 12 and shoulder portions 13 are on the outside as shown in Figure 2, the body portion of the fur coat thus being on the interior and concealed. When the garment is worn as a cloth coat, the fur sleeves 21 can be detached, or if greater warmth is desired, they can be worn inside of the cloth sleeves.

When the garment is to be worn as a fur coat,

the cloth coat is reversed so that the body portion of the fur coat will be exposed to view while the body portion of the cloth coat is on the interior and concealed. The cloth sleeves 12 are extended through the shoulder openings 19 in the manner as illustrated in Figure 5.

The detachable fur sleeves 21 are then slipped over the respective cloth sleeves 12 and the upper open ends of the fur sleeves are connected to the edges of the respective shoulder openings by the "zipper" type fastener slides 23 and 24 cooperating with the "zipper" tapes in the conventional manner.

When the fur sleeves are fastened in place, the cloth sleeves are entirely concealed and form linings for the fur sleeves and further the adjacent edges of the shoulder openings and the upper ends of the fur sleeves will be closed by the fastener means and the fur will tend to conceal the "zipper" fastener from view, so as not to detract from the appearance of the fur coat.

When it is desired to convert the garment into a fur cape, the fur sleeves 21 are detached, the cloth sleeves 12 are pulled in through the shoulder openings 19 and are tucked down between the body portions of the fur and cloth coats as shown in the full lines in Figures 9, the dotted lines in this view showing the position of the cloth sleeve when extended out through the shoulder opening.

With the cloth sleeves tucked down between the two coats the openings 19 are then closed by its "zipper" fastener thereby presenting a sleeveless cape of the type illustrated in Figure 3. The collar may be pulled upwardly if desired, as also shown in this figure.

While I have shown one fastening means for attaching the fur sleeves to the fur coat and for also closing the shoulder openings when the garment is used as a cape, it is to be understood that two pairs of fasteners may be employed, one for attaching the fur sleeves and the other, for closing the shoulder openings in the cape.

It will thus be seen from the foregoing description that I have provided a three-in-one garment that can be readily and easily converted into a fur coat, a cloth coat or a sleeveless cape thereby producing economy and saving considerable space when storing the garment and obviating the necessity of having to purchase three such separate garments.

While I have shown the preferred embodiment of my invention, it is to be understood that various changes in the size, shape and arrangement of parts may be resorted to without departing from the spirit of the invention and the scope of the appended claims.

Having thus described the invention, what I claim is:

1. A garment comprising a coat body having shoulder portions provided with arm openings, detachable sleeves connected to the shoulder portions at the edges of the respective arm openings for disposition on the exterior of the coat body when attached, and means for closing said openings when the sleeves are detached to form a cape, the means for closing the arm openings also serving as the means for attaching the detachable sleeves.

2. A garment comprising two coats of different materials arranged in superposed relation and united at their front and top portions to provide a unitary structure, one of said coats having permanent sleeves, the other coat having arm openings in its shoulder portions, and detachable

sleeves connected to the shoulder portions at the edges of the respective arm openings, the permanently connected sleeves being capable of being tucked in between the body portion of the two coats to convert the garment into a sleeveless cape when the detachable sleeves are removed.

3. A garment comprising two coats of different materials arranged in superposed relation and united at their front and top portions to provide a unitary structure, one of said coats having permanent sleeves, the other coat having arm openings in its shoulder portions, detachable sleeves connected to the shoulder portions at the edges of the respective arm openings, the permanently connected sleeves being capable of being tucked in between the body portions of the two coats to convert the garment into a sleeveless cape when the detachable sleeves are removed, and means for closing said arm openings, when the garment is worn as a cape.

4. A garment comprising a cape including a body portion and shoulders, said shoulders having arm openings, a coat including a body portion, shoulders and sleeves, said cape and coat being arranged in superposed relation and secured along their front and top portions to provide a unitary structure, the sleeves of the coat adapted to extend outwardly through the arm openings when the garment is worn as a coat, said sleeves being tucked in between the body portions of the cape and coat when the garment is worn as a cape, and means for closing the arm holes when the garment is worn as a cape.

5. A garment comprising a cape including a body portion and shoulders, said shoulders having arm openings, a coat including a body portion, shoulders and sleeves, said cape and coat being arranged in superposed relation and secured along their front and top portions to provide a unitary structure, the sleeves of the coat adapted to extend outwardly through the arm openings when the garment is worn as a coat, said sleeves being tucked in between the body portions of the cape and coat when the garment is worn as a cape, means for closing the arm holes when the garment is worn as a cape, and a single collar for the cape and the coat.

6. A garment comprising a fabric coat including a body portion, shoulders and sleeves; a fur coat including a body portion, and shoulders having arm openings, said coats being arranged in superposed relation and united at their front and top portions, to provide a unitary reversible structure, fur sleeves detachably secured to the shoulder portions of the fur coat at the arm openings, the sleeves of the fabric coat being disposed outwardly through the arm openings and the fur sleeves disposed thereover when the garment is worn as a fur coat, united collar portions at the top portions of the two coats, and means for closing the arm openings in the fur coat when the fur sleeves are detached and the sleeves of the fabric coat are tucked in between the body portions of the two coats, to produce a sleeveless cape.

7. A garment comprising a fabric coat including a body portion, shoulders and sleeves; a fur coat including a body portion, and shoulders having arm openings, said coats being arranged in superposed relation and united at their front and top portions, to provide a unitary reversible structure, fur sleeves detachably secured to the shoulder portions of the fur coat at the arm openings, the sleeves of the fabric coat being disposed outwardly through the arm openings and the fur

sleeves disposed thereover when the garment is worn as a fur coat, united collar portions at the top portions of the two coats, and means for closing the arm openings in the fur coat when the fur sleeves are detached and the sleeves of the fabric coat are tucked in between the body portions of the two coats, to produce a sleeveless cape, the means for closing the arm openings also serving as the means for attaching the fur sleeves to the fur coat.

8. In a device, as described, a convertible garment comprising a coat and a cape attached together and adapted for interchangeable use; the coat being provided with sleeves, and the cape with arm holes, the sleeves of the coat being

tucked away between the cape and said coat, when the combination is used as a cape; and means for closing the arm holes in the latter instance.

5. 9. In an invention, as claimed in claim 8, and wherein the said closing means may consist of a "zipper" arrangement.

10. 10. In an invention, as claimed in claim 8 and wherein the coat and cape are secured together at their top.

11. 11. In an invention, as claimed in claim 8 and wherein the coat and cape are secured together at their top, and having connected thereto a single collar.

15

ANNE NATHALIE CARLU.
